LIPSTICK APPLICATOR

Mona V. Eastley, Los Angeles, Calif., assignor to
Charles A. Mureau, Omaha, Nebr.

Application November 16, 1936, Serial No. 111,086

3 Claims. (Cl. 132—79)

This invention relates to a cosmetic applying device and relates more particularly to a lip rouge applicator. A general object of this invention is to provide a practical, inexpensive lip stick holder having a brush for spreading and smoothing the lip rouge after being applied by the lip stick.

In applying lip rouge it is the general practice to rub the rouge directly on the lips from a lip stick and then employ the fingertips to smooth, distribute and shape the application of rouge. This soils the fingers and rouge is often transferred from the fingers and hands to the clothing, etc. Further, it is difficult to accurately and evenly distribute the rouge and shape the rouge application with the fingertips.

Another object of this invention is to provide a lip stick holder having a conveniently located and readily available brush for smoothing and shaping the lip rouge.

Another object of this invention is to provide a lip stick holder embodying a brush that is normally enclosed and protected so that it does not soil the hands, clothing, etc., and so that it is prevented from becoming distorted and otherwise injured.

Another object of this invention is to provide a holder of the character mentioned in which the brush is enclosed in an end or false bottom of the holder and is readily projected for use by merely opening a small door or cover.

Another object of this invention is to provide a holder of the character mentioned in which the brush and the parts carrying and enclosing the brush constitute a small and compact assembly that does not materially add to the size or weight of the holder.

Another object of this invention is to provide a compact, inexpensive attachment for a lip stick holder that embodies a brush for spreading and smoothing the lip rouge and means for housing and protecting the brush.

A further object of this invention is to provide a lip stick holder attachment of the character mentioned that may be easily and quickly applied to a lip stick holder.

The various objects and features of my invention will be fully understood from the following detailed description of typical preferred forms and applications of the invention, throughout which description reference is made to the accompanying drawing, in which:

Fig. 1 is a side elevation of a lip stick holder embodying the present invention. Fig. 2 is a view similar to Fig. 1 with the cap removed from

the holder and the lip stick extended. Fig. 3 is a side elevation of the holder turned end for end and illustrating one of the brushes in a partially projected position. Fig. 4 is a view similar to Fig. 3 illustrating the said brush in the fully projected position. Fig. 5 is an enlarged fragmentary side elevation of a portion of the holder illustrating the body, the hinge connection and a portion of the cover in longitudinal cross section. Fig. 6 is a top or plan view taken substantially as indicated by line 6—6 on Fig. 3 and Fig. 7 is a fragmentary side elevation illustrating the attachment provided by the invention in position on a lip stick holder.

The present invention is adapted to be embodied in lip stick holders of various shapes and constructions and in holders having various means for projecting and retracting the lip stick. In the following detailed disclosure I will describe a typical preferred form of the invention embodied in a holder of the general character described in my co-pending application entitled Lip rouge applicator, Serial No. 111,087, filed November 16, 1936. It is to be understood that the invention is not to be construed as limited or restricted to the specific forms or applications about to be described, but is to be taken as including any features or modifications that may fall within the scope of the claims.

The more or less typical lip stick holder illustrated in Figs. 1 to 6, inclusive, of the drawing, includes a case 10, a stick 11 of lip rouge in the case 10, and a cover or cap 12. The case 10 is cylindrical and the cap 12 is slid over its outer end to normally enclose the open end of the case. The lip stick 11 is operated between the projected position and the retracted position in the case 10 by a suitable mechanism (not shown) within the case. The invention is not primarily concerned with the mechanism for feeding and retracting the lip stick 11 and the details of this mechanism are omitted from the present description. What I will term the inner end of the case 10 is closed by a closure or end 13. The end 13 may or may not be in the form of a turnable knob for actuating the means for projecting and retracting the lip stick 11. In the particular case illustrated the end 13 is a flat disc-like part having a knurled periphery. The present invention contemplates the provision of a brush and brush mounting unit on the case 10 or the cap 12, or both. Figs. 1 and 3 illustrate a unit of this character on both the case 10 and the cap 12. As the two units may be identical I will proceed with a detailed description of the brush unit on the

case 10, it being understood that such description is equally applicable to the other brush unit.

The form of the present invention illustrated in Figs. 1 to 6, inclusive, of the drawing, includes, generally, a body 15 secured to the end 13 of the lip stick case 10, a brush 16 normally within the body 15, a lid or cover 17 for the body 15 and means 18 for projecting the brush 16 simultaneously with the opening of the cover 17.

10 The body 15 of the device may be directly secured to the outer end 13 of the holder or, if desired, may be a part of the end 13. Where the body 15 is a separately formed part it may be welded or sweated to the end 13 of the holder. 15 The body 15 may be relatively thin and may be disc shaped to have its periphery flush with or stepped in from the periphery of the end 13, as illustrated in the drawing. In accordance with the invention the body 15 is shaped to receive or 20 house the brush 16 when the brush is in its retracted position. An opening 19 is provided in the body 15 to receive the brush 16. The opening 19 is an elongate diametric opening entering the body 15 from its periphery and terminating 25 before it reaches the periphery of the body at the opposite side of its axis. The end 13 closes the inner side of the opening 19. The outer side of the opening 19 is normally closed by the cover 17 as will be subsequently described. The side 30 walls of the opening 19 may converge outwardly toward the point where the opening enters the periphery of the body 15.

The brush 16 is provided to assist in spreading, smoothing and outlining the lip rouge after it 35 has been applied by the lip stick 11. The brush 16 is shaped and proportioned to be readily received in the opening 19 with suitable clearance. In accordance with the invention the brush 16 includes a shank 20 of metal or the like and a 40 tuft 21 of camel's hair or the like. The inner portion or base of the brush tuft 21 is secured in the shank 20 as by cementing, or the like. It will be noted that the brush 16 may be very simple and inexpensive.

45 The lid or cover 17 is provided to close the outer side of the body opening 19 and thus cover and protect the brush 16. The cover 17 may be a simple, flat, disc-like part adapted to lie flat against the outer surface of the body 15. It is 50 to be understood that the cover 17 may be of ornamental configuration or that it may be otherwise ornamented, if desired. As shown in the drawing the cover 17 is a plain flat disc of the same diameter as the body 15.

55 The means 18 serves to hingedly connect the brush 16 and the cover 17 with the body 15 and to automatically swing the brush 16 to the projected position illustrated in Fig. 4 when the cover is opened and to automatically return the brush 16 to its normal position in the opening 19 when the cover 17 is moved to its closed position. The means 18 includes what I will term a hinge block 22. The block 22 may be integral with the shank 20 of the brush 16 or may be 60 secured to the shank by welding or soldering. The block 22 projects laterally or at substantially right angles from the shank 20, as best illustrated in Fig. 5 of the drawing. A transverse opening 23 is provided in the block 22 to receive 65 a pivot pin or hinge pin 24. The opposite end portions of the pin 24 are carried in openings in the body 15 at opposite sides of its opening 19. It is to be noted that the opening 23 lies in a plane substantially longitudinally aligned with 70 the brush 16 and its shank 20. The pin 24

serves to pivotally or hingedly connect the block 22 and the brush 16 with the body 15.

The outer portion of the hinge block 22 is received in a notch 25 in the periphery of the cover 17. The outer portion of the block 22 has a transverse opening 26 receiving a pivot pin or hinge pin 27. The hinge pin or pivot pin 27 has its opposite end portions received in openings in the cover 17. The openings 23 and 26 are preferably substantially parallel. The inner or rear wall of the notch 25 is bevelled away to permit the required pivotal movement of the cover 17 relative to the block 22. A stop 29 is provided directly below the inner end of the hinge block 22. The corners of the hinge block 22 are preferably rounded as illustrated in the drawing. The cover 17 may be provided at its under side with a pin 30 adapted to cooperate with a socket 31 in the body 15 to releasably latch the cover in the closed position.

20 The hinge construction described above constitutes a double hinge pivotally or hingedly connecting the brush 16 and the cover 17 to the body 15 so that the brush is automatically projected and retracted upon opening and closing of the 25 cover. When the cover 17 is lifted and swung toward the open position it pivots on the pin 27 or the pin 27 pivots in its openings until the cover assumes or approaches a position at substantially right angles to the longitudinal axis of 30 the holder. At this time the bottom wall of the notch 25 contacts or engages the flat outer side of the block 22 so that continued opening movement of the cover 17 results in pivotal movement of the brush 16, together with the cover. Fig. 5 35 of the drawing illustrates the rear wall of the notch 25 engaging the outer side of the block 22 and illustrates how opening movement of the cover 17 effects outward swinging movement of the brush 16. The cover 17 may be swung to a 40 fully open position where it lies adjacent the periphery of the case 10 at which time the outer side of the block 22 comes in flat contact with the stop 29. This engagement limits further opening movement of the cover 17 and stops the 45 brush 16 in the position illustrated in Fig. 4 where it projects from the end of the holder and is substantially parallel with its longitudinal axis. In practice the pin 24 may fit the opening 23 rather snugly so that the brush 16 remains in 50 position until deliberately or intentionally shifted. It will be seen that opening movement of the cover 17 to a fully open position automatically moves the brush 16 to a position where it projects from the end of the holder to be conveniently exposed for use.

55 After the brush 16 has been used, the cover 17 may be swung from the open position illustrated in Fig. 4 toward the closed position. This movement of the cover 17 continues without any 60 change in the position of the brush 16 until the inner or under side of the cover 17 engages the brush. During the remainder of the closing movement of the cover 17 the cover directly pushes the brush 16 inwardly into the opening 65 19. Thus, when the cover 17 reaches its closed position the brush 16 is in its retracted position within the opening 19.

70 Fig. 7 of the drawing illustrates the invention embodied in an attachment adapted to be readily applied to the end part of a typical lip stick holder. In the structure illustrated in Fig. 7 the body 15, the cover 17, the brush 16 and the means 18 may be the same as described above. The body 15 is provided with a releasable se- 75

curing member 35. The member 35 may be suitably secured to the body 15 or may be formed as an integral part of the body. The releasable attaching member 35 has a plurality of depending fingers 36. The fingers 36 are shaped to readily grip the end or a similar part of a typical lip stick holder H. The fingers 36 may be flexible and resilient and may be formed to readily grip or embrace an end portion of the holder H to secure the body 15 to the holder. It will be apparent how the fingers 36 may be formed and shaped to dependably secure the body 15 to the end part of a holder H by merely pressing the fingers 36 over the holder. The fingers 36 may be such that the attachment may be readily removed from the holder H, if desired.

It is believed that the utility and practicability of the present invention will be readily understood from the foregoing detailed description. Referring to Figs. 1 to 6, inclusive, the body 15 housing the brush 16 and the cover 17 form a small compact assembly at one end of the lip stick holder. This assembly does not materially add to the size or weight of the holder and may be readily secured to or provided on the holder end 13. As described in detail above, the cover 17 may be swung from its closed position to its fully open position illustrated in Fig. 4 to project the brush 16 at the end of the holder. When the brush 16 is in this projected position it may be conveniently employed to spread and shape the lip rouge. The brush 16 projects from the end of the holder adjacent its periphery and, therefore, is fully exposed for convenient use. Following the use of the brush 16 it is only necessary to close the cover 17. Closing of the cover 17 automatically moves the brush 16 back into the body opening 19 as described in full above. The brush 16 is normally housed and fully protected in the opening 19 so that it is not distorted or soiled. The brush may be projected and retracted in the manner described without direct contact and, therefore, without the transference of the lip rouge to the fingers of the user. The lip stick holder and the at-

tachment of the invention are simple and inexpensive and may be readily applied to or embodied in lip stick holders of various natures.

Having described only typical preferred forms and applications of my invention I do not wish to be limited or restricted to the specific details herein set forth, but wish to reserve to myself any variations or modifications that may appear to those skilled in the art or fall within the scope of the following claims.

Having described my invention, I claim:

1. An applicator for use on a cosmetic case comprising a part on the case having an opening, a brush to be received in the opening, a hinge block on the brush pivotally supported on said part, a cover for the opening, and means pivotally connecting the cover with the brush whereby pivoting of the cover from the closed position to the open position engages the cover against the block to pivot the same and project the brush. 10

2. An applicator for use on a cosmetic case comprising a part on the case having an opening, a brush to be received in the opening, a hinge block on the brush pivotally supported on said part, a cover for the opening, means pivotally connect- 20

ing the cover with the brush whereby pivoting of the cover from the closed position to the open position engages the cover against the block to pivot the same and project the brush, and a stop 25 limiting pivotal movement of the brush to stop 30 the same in a position where it projects longitudinally from the case.

3. An applicator for use on a cosmetic case comprising a part on the case having an opening, a brush to be received in the opening, a block on 35 the brush pivotally connected with said part, a cover for said opening, and means pivotally connecting the cover with said block for movement about an axis substantially parallel with the axis of pivotal movement of the brush whereby the 40 cover engages and pivots the block during opening movement of the cover to project the brush and the cover moves the brush back into the opening during closing movement of the cover.

MONA V. EASTLEY. 45
